Nicholas Meyer, inventor
by Geo. E. Brown, Atty.

United States Patent Office.

NICHOLAS MEYERS, OF BUFFALO, NEW YORK, ASSIGNOR TO GLOBE SEWING-MACHINE COMPANY, OF SAME PLACE.

Letters Patent No. 99,783, dated February 15, 1870.

IMPROVEMENT IN SEWING-MACHINE.

The Schedule referred to in these Letters Patent and making part of the same.

To all whom it may concern:

Be it known that I, NICHOLAS MEYERS, of Buffalo, in the State of New York, have invented new and useful Improvements in Sewing-Machines; and I do hereby declare, that the following is a full, clear, and exact description of the same, reference being had to the accompanying drawings and letters of reference marked thereon, making a part of this specification, in which—

Figure 1 is a side elevation of the mechanism above and below the supporting table;

Figure 2, a plan view of the mechanism on the under side of the supporting table inverted;

Figure 3 is a detached plan of the slide and adjustable cloth plate;

Figure 4, a vertical section, showing more particularly the eccentric disk with its curved side, and the tube with its pressure spring;

Figure 5, a detached vertical section, showing the recessed presser-bar, enclosed feed-lever and stitch-gauge; and

Figure 6, a side elevation, showing the flange beneath the table, the sliding needle-chamber block and its operating lever.

To enable those skilled in the art to make and use my invention, I now proceed to describe its construction and operation.

Similar letters in the drawings refer to like parts.

This invention consists of divers new and useful devices relating, in part, to sewing-machines generally, and in part, to a sewing-machine which produces either the lock-stitch or the double-loop stitch at pleasure.

This invention includes a mechanism for communicating movement from the motor-shaft to the shuttle-carrier; also a needle-clamp in the lower part of the needle-bar, which admits of a movement of the needle in a horizontal direction toward or from the shuttle; also a controller-bar, pivoted upon the lower side of the supporting table, and jointed to the vibrating block that carries the looper, which forms the loop-stitch, for the purpose of directing such looper in the proper path; also a needle-chamber block, capable of being lowered far enough to leave a sufficient interval between its upper end and the lower surface of the supporting table, in which the curved looper may enter and catch the bight of the upper thread, which block may be raised when the looper is not to be used, so that its chamber shall be continuous with the needle-hole in the cloth-plate; and finally, a mechanism on the lower side of such table, for communicating the motion of the shuttle-driving apparatus to the said vibrating block carrying the looper, said mechanism being so contrived that it may be disconnected, at any time, from such shuttle-driving apparatus, when the latter only is to be used.

In the drawings—

A is the motor-shaft, bearing at one end the eccentric disk *a*, and at the other end the cam-groove cylinder *a'*.

The cam groove *a''* operates the vibrating lever *a''*, the lower end of which is jointed to one extremity of the split rod *b*, on the under side of the table *B*, which rod is jointed at its other extremity to one end of the elbow-lever *b'*, the opposite end of which is pivoted to the split rod *b''*, which connects the elbow-lever with the shuttle-carrier *c*. The vibrating motion of the elbow-lever is thus converted into the reciprocating motion required by the carrier.

The connecting rods *b b''* are each formed of two separate bars placed side by side and bolted together, a sufficient interval being left between the separate rods to admit of their being tightened upon the parts to which they are articulated, as the joints wear loose. It is found expedient in practice to keep the needle, whatever its size, at a point where the shuttle may pass as near it as practicable, in order that the latter may always go through the bight of the upper thread.

It is desirable therefore to provide some means of adjusting the needle horizontally with respect to the shuttle.

The means I employ consists of a tube, *e*, having a milled exterior flange at one end and threaded on its outer surface, so that it may be screwed into a horizontal orifice made crosswise of the needle-bar *e'*, and near its lower extremity.

In the tube *e* is placed a pin, *e''*, bearing at one end a vertical plate, *e'''*, and threaded exteriorly, so as to receive a nut, *e⁴*, upon its outer end, at the opposite side of the needle-bar.

The pin *e''* has an orifice made vertically through it, wherein is placed the needle *e⁵*, which is clamped between the plate *e'''* and the flange of the tube *e*.

On loosening a little the nut *e⁴*, the tube *e* may be screwed out of the needle-bar, carrying before it the needle, pin *e''* and vertical plate *e'''*, the former still clamped between the other two in a horizontal direction, until the movement is checked by the striking of the nut *e⁴* against the needle-bar. If the adjustment be not then complete, the nut may be again loosened. On screwing the tube *e* back through the needle-bar, the pin *e''* becomes slackened, and should be made to follow the tube by pressure. The slack is to be taken up by the nut *e⁴*.

The eccentric disk *a* at the end of the motor-shaft operates the feed-mechanism.

The disk is beset with a curved rider, *h*, so shaped as to receive motion in three directions, one upward, and two lateral.

The curved rider projects from the upper end of a tube, *h'*, from the lower end of which projects down-

ward a slotted plate, h^3 , through which a pivot passes into the framework O .

A pin extending from the lower extremity of the slotted plate h^3 through an orifice in the side of the presser-bar i , passes into and makes a joint with the upper end of the feed-lever h , which bears the toothed feed-plate h^4 on its lower end, and is itself pivoted in the said presser-bar. Thus the three motions of the curved rider h^4 are communicated to the feed-plate through the compound lever $h^4 h^5$; but as the weight of the connecting system of leverage is insufficient to insure the taking hold of the cloth by the toothed feed-plate, the tube h^5 is provided with an inner spiral spring, h^6 , the extremities of which are attached, respectively, to the pivot of the slotted plate h^3 and a sliding head, h^6 , within the tube, which head is connected with a screw, h^7 , in the top of the tube. The raising and lowering of the sliding head by means of the screw, regulates the tension of the spring and the consequent pressure of the feed-plate upon the cloth.

When it is desired to produce the looped stitch the shuttle is removed, and in its place I employ the curved looper l projecting from one end of the block l' , the latter being pivoted to the elbow-lever l^2 , which receives a vibratory motion from the connecting bar l^3 . The looper is caused to traverse the proper curve by means of a controller-bar, l^4 , pivoted at its ends to the block l' and the supporting table, respectively. The looper moves in a recess cut for the purpose out of the under part of such table.

A vertical flange, k , runs crosswise of and beneath the table, and forms a face for the shuttle. The middle portion k^1 of the flange k is separate from the rest, forming a block, sliding vertically in the flange under the operation of a lever, k^2 , jointed to the block and pivoted upon the flange.

The k^1 of k^1 contains a vertical recess, k^2 , which forms an inner needle-chamber, being entered by the needle every time the latter passes through the cloth-plate. When the shuttle is in use, and the curved looper out of gear, the block k^1 should be brought close up against the under side of the slide d' , as shown in fig. 6, so that its chamber may be continuous with the needle-hole of the latter. But when the loop-stitch is to be formed, this location of the block k^1 would prevent the looper from crossing the path of the needle k to catch the bight of the upper thread. The block is then, consequently, lowered by means of the lever k^2 , far enough to permit the looper to have free play above it.

The connecting bar l^3 , which is pivoted, as before stated, at one end to the elbow-lever l^2 , is curved in sickle-form at its other end, as shown in fig. 2, and has a notch, l^4 , at such extremity.

An arm, m , placed with such tightness on the pivot of the elbow-lever b' as generally to turn with it, but on occasion upon it, has a pin projecting upward from its free end.

The curved part of the connecting bar l^3 has a sliding motion upon the pivot of the opposite extremity

of the bar, and its notch l^4 may consequently be moved upon or away from the pin of the arm m , and locked by the slide m' and set-screw m'' , operating immediately upon the arm m^3 of the curved part of the connecting rod, so as to be incapable of further lateral motion, but capable of longitudinal movement. When the connecting rod l^3 is thus locked upon the arm m , the vibration received by the latter from the elbow-lever b' is communicated to the former, and through it indirectly to the curved looper, which is thus operated by direct connection with the shuttle-driving apparatus. If the slide m' be unloosed, the curved part of the connecting rod l^3 be moved away from the pin of the arm m , and the connecting rod be shoved endwise toward the curved looper as far as it will go, the looper-block is, by the movement, folded partially upon its elbow-lever, the looper withdrawn from above the needle-chamber block k^1 and the formation of the loop-stitch brought to an end.

What I claim as new, and desire to secure by Letters Patent, is—

1. The motor-shaft A , vibrating lever a'' , connecting rods b'' , elbow-lever b' , and shuttle-carrier c , all constructed and arranged to operate in combination, substantially as described.

2. The combination of the needle-carrying bar with the flanged tubular screw e and needle-confining block, the latter having a screw projecting laterally therefrom passing through the tubular screw, and held by nut e' , all constructed substantially as described, for the purpose of adjusting the position of the needle with reference to the carrying-bar.

3. The pivoted controller-bar l^4 , combined with the vibrating looper-block l^1 and elbow-levers $l^2 l^3$, so as to guide the curved looper, substantially as specified.

4. The covering plate d' , having a hole for the needle, the face of the shuttle-race, and the grooved adjustable block k^1 in the face of the race, when so combined and arranged, substantially as described, that the groove in the block coincides with the hole in the covering plate, and that the block may be adjusted in position below the covering plate, to make the race face continuous for the operation of the shuttle, or leave an opening in the race face, through which the looper may operate when the shuttle is removed.

5. The connecting bar l^3 , having the slot l^4 and arm m^3 , adjusting mechanism $m^1 m^2$ and arm m , connected with the shuttle-operating lever b' , all combined for the purpose of throwing the looper in or out of operation, as described.

6. The sliding lever h' , provided with the rider h^4 , and combined with the feed-lever h , working on the adjustable fulcrum i , the whole being operated by the eccentric a upon the motor-shaft A , substantially as described.

NICHOLAS MEYERS.
